UNITED STATES PATENT OFFICE.

HENRY S. BREWINGTON, OF BALTIMORE, MARYLAND.

PAPER CONTAINER.

1,125,644.

Specification of Letters Patent.

Patented Jan. 19, 1915.

Application filed July 5, 1913. Serial No. 777,417.

To all whom it may concern:

Be it known that I, HENRY S. BREWINGTON, a citizen of the United States, residing at Baltimore city, State of Maryland, have 5 invented certain new and useful Improvements in Paper Containers, of which the following is a specification.

This invention relates to receptacles or containers specially adapted to contain 10 solid, pulverulent, granular, liquid and semi-liquid substances.

An object of the invention is to provide a receptacle or container of simple and inexpensive construction which may be readily 15 formed from paper, wood pulp or, if desired, a more durable and stronger material such as metal.

Another object is to provide a receptacle formed of a single piece or blank and consisting 20 essentially of a body and ends, the latter being greatly strengthened and reinforced by the peculiar formation thereof.

With these objects in view, the invention 25 consists in the improved construction and arrangement of the parts of a device of the character specified, which will be herein-after fully described, and afterward specifically claimed.

In order that the construction and operation 30 thereof may be readily comprehended, I will now proceed to fully describe my invention in connection with the accompanying drawings, which illustrate an approved embodiment thereof, and in which 35 drawings,

Figure 1 represents a vertical central sectional view through the receptacle, Fig. 2 a side elevation partly in section showing the upper end partly open. Fig. 3 a bottom 40 plan view, and, Fig. 4 a fragmentary sectional view of a modified means for closing the end of the receptacle.

Like reference characters mark the same 45 parts in all the figures of the drawings, wherein the numeral 5 indicates the body portion, which is here shown cylindrical but may be formed in any desired shape and with or without seams.

The body portion 5 may be formed of 50 any desired length, and the end portions 6 thereof are turned inwardly on a circumferential line spaced a distance from the extremities of the body, and representing the radius of the receptacle. The inwardly 55 turned portions 6 at the ends of the receptacle are folded or crimped so that nor-

mally, or when unsecured, they assume the position shown at the upper end of the receptacle in Fig. 2.

Various means may be employed for securing and sealing the folded ends 6, and in Figs. 1 and 3, I have shown the employment of a suitable rivet or plug 7 which may be formed of metal, wood-pulp or any other suitable material and is headed at either 60 end. After the rivet or plug 7 is inserted in the central opening of the ends, it is obvious that the diametrical measurement thereof will be materially increased, and consequently said ends are arched or bulged 65 inwardly, as clearly illustrated in the sectional view of Fig. 1. Such bulging of the ends materially increases the strength and rigidity and insures against outward exertions of the contents of the receptacle. A 70 circular partition 8, shown in dotted lines in Fig. 1 may be employed if desired, said partition engaging over the apex of the ends and consequently directs all exertions or strains from within thereon. Preferably, I 75 employ a fastener or plug 10, of wood or other suitable material, in place of the rivet or plug 7 at the top of the receptacle for convenience in opening the receptacle. The shank of the fastener is positioned through 80 the central opening in the end and is provided with a pair of spaced flanges 11 engaging the folds of the end similarly to the heads of the rivet 7. The outer end of the shank is provided with a handle or knob 85 12 adapted to be grasped for withdrawing the fastener to open the end.

In the modification shown in Fig. 4, the ends 6 are turned inwardly on a circumferential line of the body portion 5 a greater 90 distance from the extremities of the latter than the ends of the receptacle shown in the above described figures, whereby the ends of the folds will lie in abutment when said ends are bulged inwardly as shown. For securing the ends thus formed a suitable adhesive 95 may be employed, and for protecting the adhesive from the action of the contents of the receptacle a partition 9 is preferably employed.

While I have specifically described the exact construction and arrangement of the component parts of my invention, it will be obvious to those skilled in the art to which the invention most nearly appertains, that 100 slight changes and variations may be made therein, within reasonable limitations, with-

out departing from the spirit and scope of the invention.

Having thus fully described my invention, what I claim and desire to secure by 5 Letters Patent of the United States is:—

1. A receptacle consisting of a body portion having ends formed integral therewith continuously around said body portion, said ends being crimped to afford corrugated 10 ends which when turned inward toward the center of the receptacle clusters the free ends of the corrugations in close relation and in vertical lines, the sides of the corrugations gradually changing from a vertical 15 to substantially a horizontal position from the cluster to the edge of the receptacle, and means for securing said ends in a closed position.
2. A receptacle consisting of a body portion having ends formed integral therewith continuously around said body portion, said ends being crimped to afford corrugated 20 ends which when turned inward toward the center of the receptacle clusters the free ends of the corrugations in close relation and in vertical lines, the sides of the corrugations gradually changing from a vertical 25 to substantially a horizontal position from the cluster to the edge of the receptacle, and means for securing said ends in a closed position bulging inwardly.
3. A receptacle consisting of a body portion having ends formed integral therewith continuously around said body portion, said 30 ends being crimped in parallel lines to afford corrugated ends which when turned inward toward the center of the receptacle clusters the free ends of the corrugations in close relation and in vertical lines, the sides 35 of the corrugations gradually changing from a vertical to substantially a horizontal position from the cluster to the edge of the receptacle, and means for securing said ends in a closed position.
4. A receptacle consisting of a body portion having ends formed integral therewith continuously around said body portion, said ends being crimped to afford corrugated 40 ends which when turned inward toward the center of the receptacle clusters the free ends of the corrugations in close relation and in vertical lines, the sides of the corrugations gradually changing from a vertical 45 to substantially a horizontal position from the cluster to the edge of the receptacle, and means for securing said ends in a closed position bulging inwardly, and a partition in said body portion adjacent to one of said ends.
5. A receptacle consisting of a body portion having ends formed integral there-

with continuously around said body portion, said ends being crimped to afford corrugated ends which when turned inward toward the center of the receptacle clusters 65 the free ends of the corrugations in close relation and in vertical lines, the sides of the corrugations gradually changing from a vertical to substantially a horizontal position 70 from the cluster to the edge of the receptacle, and a removable means for securing said ends in a closed position.

6. A receptacle consisting of a body portion having ends formed integral therewith continuously around said body portion, said 75 ends being crimped to afford corrugated ends which when turned inward toward the center of the receptacle clusters the free ends of the corrugations in close relation and in vertical lines, the sides of the corrugations 80 gradually changing from a vertical to substantially a horizontal position from the cluster to the edge of the receptacle, and a removable means having a handle for securing said ends in a closed position.

7. A receptacle consisting of a body portion having ends formed integral therewith continuously around said body portion, said ends being crimped to afford corrugated 90 ends which when turned inward toward the center of the receptacle clusters the free ends of the corrugations in close relation and in vertical lines, the sides of the corrugations gradually changing from a vertical to substantially a horizontal position from the 95 cluster to the edge of the receptacle, and means for securing said ends in a closed position embodying a plug inserted between the clustered ends of said crimps which prevents an outward movement of the ends of 100 the receptacle against other than a positive force.

8. A receptacle consisting of a body portion having crimped ends which are integral throughout their entire area, the crimps 105 in said ends being formed with abutting edges which when brought into contact with each other by folding the ends inwardly form a complete closure, and means for securing said ends in a closed position embodying a plug having spaced flanges for engaging the inner and outer sides of and inserted between the abutting edges of said crimps which prevents an outward movement of said ends against other than a positive 110 force.

In testimony whereof I affix my signature in presence of two witnesses.

HENRY S. BREWINGTON.
